ELECTRODE HOLDER

Herbert H. Peyreferry, Eddystone, Pa.

Application January 26, 1950, Serial No. 140,601

3 Claims.

(Cl. 219—8)

1

This invention relates to new and useful improvements and structural refinements in electrode holders, more particularly, holders for welding electrodes, and the principal object of the invention is to provide a holder of the character hereinabove described, which is very simple in construction and operation, which does not require lubrication or adjustment, which, being properly ventilated and insulated, safeguards the operator against the effect of heat and electric current, and which lends itself to economical manufacture.

An important feature of the invention resides in the provision of releasable means for frictionally retaining an electrode in the holder, while another feature resides in the structural arrangement of the insulating means.

With the above more important objects and features in view and such other objects and features as may become apparent as this specification proceeds, the invention consists essentially of the arrangement and construction of parts as illustrated in the accompanying drawings, in which:

Figure 1 is a perspective view of the invention.

Figure 2 is a longitudinal sectional view thereof.

Figure 3 is a transverse sectional view, taken substantially in the plane of the line 3—3 in Figure 2, showing the electrode in place.

Figure 4 is a transverse sectional view, taken substantially in the plane of the line 4—4 in Figure 2, and

Figure 5 is a perspective view of the barrel used in the invention, the same being shown in an inverted position.

Like characters of reference are employed to designate like parts in the specification and throughout the several views.

Referring now to the accompanying drawings in detail, the invention consists of an electrode holder designated generally by the reference character 10, the same embodying in its construction a metallic barrel 12 having a closed end 14 and an open end portion 16 which is tapered as shown in Figure 2 so as to accommodate a conventional connector 18 for securely attaching an electric conductor 20 to the barrel. The connector 18 is tightened into position by means of a nut 22 which is disposed within the barrel, it being noted that the latter is provided with a longitudinally extending trough or recess 24 so that access may be had to this nut as well as to other components, hereinafter described, which the interior of the barrel contains.

The closed end portion of the barrel 12 is provided with a pair of diametrically opposed, longitudinally extending slots 26 to accommodate an electrode 28 which may be inserted in the slot and disposed at an angle to the longitudinal axis of the barrel, there being provided means for frictionally engaging the electrode so as to removably retain the same in position.

These means consist of a resilient strap or leaf 10 spring 30 which has one end portion thereof secured as at 32 to the inner wall of the barrel tongue 12, while a pressure pad 34 is secured as at 36 to the free end portion of the spring. The pad 34 is disposed in the closed end portion of the barrel between the slots 26, and the resiliency of the spring 30 is such as to urge the pad 34 upwardly as shown in Figure 2 by the arrow 38.

However, means are provided for depressing the spring and the pad thereon, these means consisting of a depressible releasing knob 40 which is secured to an intermediate portion of the spring 30 by suitable screws 42 and projects outwardly from the barrel as shown.

It will be apparent from the foregoing that the knob 40 may be depressed so as to move the pad 34 below the slots 26, whereupon the electrode 28 may be inserted in the slots and the knob 40 released, so that the pressure pad 34 engages the underside of the electrode as shown in Figure 3, thus frictionally retaining the electrode in position by the resiliency of the spring 30. Similarly, the knob 40 may be depressed to facilitate removal of the electrode, as will be clearly apparent.

Insulation is provided on the barrel to protect the operator from the effects of heat and electric current, this insulation comprising a jacket of insulating material, consisting of a jacket section 44 and a jacket section 46, both of which are grooved as shown, so as to facilitate dissipation of heat and, also, to prevent slipping of the holder when it is held in the hand. The barrel 12 as well as the jacket section 44 are provided with registering openings to receive the knob 40, the jacket section 44 also being equipped with a pair of diametrically opposed, longitudinally extending slots 48 which are in register with the aforementioned slots 26 in the barrel, to receive the electrode. Moreover, these slots also serve to connect the interior of the barrel with the atmosphere, thus assisting in the dissipation of internal heat.

An insulating disk 50 is secured by a screw 52 to the closed end 14 of the barrel 12, the inner surface of the disk being provided with a trans-

verse rib 54 which is receivable in a transverse groove 56 in the end 14 of the barrel, whereby rotation of the disk on the barrel is prevented.

The front end or edge of the jacket section 44 abuts a marginal edge portion of the disk 50 which is sufficiently large in diameter to project beyond the lateral wall of the barrel 12, while the rear end of the jacket section 44 is counterbored as at 58 to receive an annular, interfitting shoulder 60 on the front end of the jacket section 46. The latter is fastened to the barrel 12 by a set screw 62 and is open at its rear end, so as to accommodate the connector 18 and the conductor 20, as shown in Figure 2.

It is believed that the advantages and use of the invention will be clearly apparent from the foregoing disclosure and accordingly, further description thereof at this point is deemed unnecessary.

While in the foregoing there has been shown and described the preferred embodiment of this invention, it is to be understood that minor changes in the details of construction and arrangement of parts may be resorted to without departing from the spirit and scope of the invention as claimed.

Having described the invention, what is claimed as new is:

1. An electrode holder comprising an elongated barrel of conductive material having a pair of diametrically opposed slots in one end thereof, said barrel further including an elongated, central, troughed portion, a tongue integral with and extending from the end of said barrel remote from said slotted end and overlying a portion of said troughed portion, parallel, inwardly directed flanges on end of said tongue forming an axially extending channel-shaped groove on said tongue, a resilient strap having one end received in said groove and having its other end terminating between said diametrically opposed slots to resiliently engage a welding rod extending through

said slots, said one end of said strap being secured in said groove and being maintained against lateral movement by the walls of said inwardly directed flanges, said barrel having an opening therein intermediate its ends on the side wall portion opposite said trough, a strap release knob slidably and guidably received in said opening and secured to said strap intermediate its ends, an insulative sheath disposed about said barrel and having an aperture therein conforming to and registering with said barrel opening, said knob slidably and guidably extending through said sheath aperture to non-slidably and non-rotatably retain the sheath on the barrel, a conductor secured to said remote end of said barrel, said remote end having an axial bore therein, said conductor being received in said bore.

2. The combination of claim 1 wherein the slotted end of said barrel has a transverse groove therein, an insulating disk secured to said end, said disk including a transverse rib, said rib being received in said transverse groove to prevent rotation of said disk.

3. The combination of claim 1 wherein said axial bore is of frusto-conical shape.
